Modern Living, Inc., Hollywood, Calif., a corporation
of California

Filed Jan. 31, 1962, Ser. No. 68,590

Term of patent 14 years

(Cl. D57—1)

Fig. 1.

Fig. 4.

FIG. 1 is a reduced scale perspective view of a pair of spectacles for eye make-up showing my new design;

FIG. 2 is a full scale top plan view thereof;

FIG. 3 is a full scale front view thereof; and

FIG. 4 is a full scale side elevational view thereof.

The side not shown is substantially like the side shown.

The dominant features of my design reside in the portions shown in full lines.

I claim:

The ornamental design for a pair of spectacles for eye make-up, substantially as shown and described.
